O. CROCKETT

SAFETY CRANKING DEVICE

Filed July 26, 1921

Patented May 22, 1923.

1,456,481

UNITED STATES PATENT OFFICE.

OSCAR CROCKETT, OF KANSAS CITY, MISSOURI, ASSIGNOR OF ONE-HALF TO WALTER B. CROCKETT, OF KANSAS CITY, MISSOURI.

SAFETY CRANKING DEVICE.

Application filed July 26, 1921. Serial No. 487,788.

To all whom it may concern:

Be it known that I, OSCAR CROCKETT, a citizen of the United States, residing at Kansas City, in the county of Jackson and 5 State of Missouri, have invented certain new and useful Improvements in Safety Cranking Devices, of which the following is a specification.

The present invention relates to a safety 10 construction for manually operated engine cranking devices such as are commonly employed for starting internal combustion engines, and has for its object to provide a construction of this character which embodies 15 novel features whereby it will act very quickly as well as in a positive and reliable manner to disengage the hand crank from the engine shaft and thereby prevent injury to the operator in the event the engine back-fires.

I am aware of the fact that there are prior 20 patents upon engine cranking devices which have this general object in view, although the constructions of these prior devices are 25 not entirely satisfactory and are open to quite a number of practical objections. In a device of this character the clutch mechanism must be one that is absolutely reliable in its operation and which will act immediately 30 without any reverse movement in order that the hand crank may be disengaged from the engine shaft before it has made more than a small fraction of a backward revolution when the engine back-fires.

35 There is always a certain amount of back play in a pawl and ratchet construction, and the shock incident to use in a device of this character is such that breakage of some of the parts in a pawl and ratchet construction 40 would be liable to take place. Furthermore, the device must be simple in its construction and adapted to be applied without any material changes or alterations to those types of engines which are already in extensive use.

The object of the present invention has been to provide a safety cranking device 45 which is free from the objectionable features found in prior devices having the same object in view, and which can be applied without difficulty to the conventional cranking devices of engines and automobiles.

With these and other objects in view, the invention consists in certain combinations 50 and arrangements of the parts as will be

shown more fully as the description proceeds, the novel features thereof being pointed out in the appended claims.

For a full understanding of the invention, reference is to be had to the following description and accompanying drawings, in which:

Figure 1 is a front elevation of a safety cranking device constructed in accordance with the invention, portions being broken away and a fragmentary portion of an automobile frame to which the device is applied being indicated by dotted lines.

Figure 2 is a side elevation of the safety cranking device, portions of the crank being broken away.

Figure 3 is a vertical sectional view through the bearing plate and associated clutch mechanism, the section being taken on the line 3—3 of Figure 1, and

Figure 4 is a top plan view of the bearing member.

Corresponding and like parts are referred to in the following description and indicated in all of the views of the drawings by like reference characters.

Referring to the drawings, which illustrate a preferred embodiment of the invention, the numeral 1 designates a hand crank which is provided at the inner end of the shaft portion thereof with a conventional clutch member 2 for engagement with the engine shaft (not shown). The shaft portion of the hand crank 1 extends through a bearing plate 3 which is suitably secured to the frame of the engine and the crank is mounted to have both a sliding movement and a rotary movement. The sliding movement enables it to be moved into and out of clutch engagement with the engine shaft in the usual manner, while the rotary movement is necessary for turning the engine shaft when cranking or starting the engine. This is the usual manner of constructing and mounting these hand cranks and this part of the construction will undoubtedly be clearly understood without further description.

The bearing plate or member 3 which is used in carrying out the present invention has a special formation, having one face thereof recessed to provide a chamber within which a clutch disc 4 is mounted. A retaining plate 5 which is detachably secured to the bearing member 3 by suitable fasten-

ing members such as the screws 6 is utilized to keep the clutch disc in operative position within the recess, and this retaining plate is provided with a central opening through 5 which a hub member 7 which is integral with the clutch disc projects. The bearing plate 3 fits against the front of a portion of the frame of the automobile, such as that indicated at 8 by dotted lines, and is provided 10 with integral ears 9 which project laterally from opposite sides thereof and are also deflected rearwardly, said ears having openings therein for engagement with fastening members such as the bolts, 10 by means of which the bearing member is 15 rigidly secured in position. The bearing member is preferably constructed so that it can be substituted for the usual bearing found upon automobiles, although the arrangement is such that the bearing plate is 20 larger than the conventional bearing. This enables a comparatively large clutch disc 4 to be utilized, and owing to the fact that the clutch members act at a distance from the shaft they have a more powerful and 25 effective clutching action and are more dependable than they would be if arranged close to the shaft.

The periphery of the clutch disc 4 is provided 30 with a plurality of cam notches 11 which receive clutch balls 12. Springs 13 are interposed between these clutch balls and the shoulders at the large ends of the cam notches, and the clutch balls are thus 35 always held in proper position to be instantly brought into action upon any tendency to turn the clutch disc in a backward direction. The arrangement of the cam notches and clutch balls is such that the 40 clutch plate is free to turn in the same direction as the engine shaft, although it is positively locked against turning in the reverse direction. The conventional construction 45 of engine is such that they are intended to operate in a clock-wise direction, and the arrangement of the cam notches shown on the drawings is such that the clutch disc 4 is free to turn in a clock-wise direction although it is locked against rotation in a 50 counter-clock-wise direction.

The hub members 7 of the clutch disc extends 55 forwardly beyond the retaining plate 5 and is provided with a series of cam notches 14 which are disposed reversely with respect to the similar cam notches of the engine shaft engaging clutch 2. These notches 14 engage lateral projections upon the shaft portion of the hand crank and co-operate therewith to move the hand crank 60 longitudinally and immediately disengage it from the engine shaft upon any back firing of the engine or tendency of the engine shaft to rotate in a counter-clock-wise direction. In the present construction a pin 65 15 extends laterally through the shaft por-

tion of the hand crank and the projecting ends of this pin are provided with anti-friction rollers 16. A spring (not shown) which may be of any conventional type, may be associated with the hand crank for moving the shaft portion thereof longitudinally to hold the clutch member 2 thereof normally disengaged from the engine shaft. 70

In order to crank the engine the hand crank is moved inwardly and brought into 75 a clutch engagement with the engine shaft. This movement of the hand crank simultaneously brings the projecting ends of the pin 15 into the cam notches 14 of the hub 7. Upon rotation of the hand crank in a clockwise direction to start the engine, the ends of the pin 15 engage the square ends of the notches 14 and cause the hub 7 and clutch disc 4 to rotate with the hand crank. If the engine starts in the proper manner the hand 80 crank 1 is disengaged from the engine shaft by the teeth of the clutch 2 in the usual manner. However, if the engine back-fires and the engine shaft starts to rotate in a counter-clock-wise direction the clutch balls 12 instantly come into action to prevent any corresponding rotation of the clutch disc 4 and hub member 7. The hand crank 1 then moves 85 independently of the clutch disc 4, with the result that the anti-friction rollers 16 ride upon the inclined sides of the cam notches 14, and move the hand crank longitudinally to disengage it from the engine shaft. The inclined ends of the cam notches 14 are arranged at a sharp angle so that the hand 90 crank is disengaged from the engine shaft before it has made more than a very small fraction of a backward turn, and all possibility of injury to the operator is thereby avoided. This action is not only quick but is also positive for the reason that the clutch 95 balls 12 are always held in position for action by the springs 13 and the clutch disc 4 is sufficiently large to admit of the clutch balls being arranged at a comparatively 100 great distance from the axis of the shaft. Furthermore, the safety device has a simple and sturdy construction which will withstand hard usage and which can be readily 105 substituted for the conventional hand cranking device. 110

Having thus described my invention what I claim as new and desire to secure by Letters Patent is:

1. In a safety cranking device for engines, the combination with a starting crank provided with a clutch member adapted to engage the engine shaft, a bearing member on which said starting crank is slidably and rotatably mounted, said bearing member being formed with a depression or recess, a clutch disk within said recess or depression and clutch means interposed between the clutch disk and the bearing member, said clutch means permitting movement of the 115 120 125 130

- clutch member in one direction only, said clutch disk having a hub portion with notches therein having cam portions, projections on said starting crank to engage said 5 notches upon movement in one direction and to be forced from said notches by said cam portions upon movement in the other direction, and a cover plate for said bearing member, said cover plate being apertured to receive the hub portion of the clutch disk and provide a bearing therefor and to retain said clutch disk in proper position within said bearing.
2. In a safety cranking device for engines, 10 the combination with a starting crank adapted to engage the crank shaft of an engine upon longitudinal movement thereof in one direction and disengage said crank shaft upon movement in the other direction, a bearing member for said starting crank fixed to the frame of the engine, said bearing member being formed with a disk terminating in a flanged rim having an internal concave faced rim forming a circular race, 15 a clutch disk having peripheral cam faces circumferentially concaved, and clutch means retained between said concave rim and said concave cam faces adapted to positively clutch the same upon movement in one direction and unclutch it upon movement in the other direction, said clutch disk being loosely journaled on said starting crank and having a reduced hub portion extending laterally therefrom, said hub portion being formed 20 with notches having cam surfaces adjacent thereto, lateral projections on said starting crank adapted to engage said notches upon movement in one direction and be forced therefrom by said cam portions upon move- 25
- ment in another direction, an apertured retaining plate for said clutch disk, said retaining plate providing a journal for said hub portion, and means to secure said plate to said bearing member. 30
3. In a safety cranking device for engines, 40 the combination with a hand crank mounted to rotate and move longitudinally and having a clutch member adapted to engage the engine shaft, a comparatively large recessed and fixedly mounted bearing member, a 45 clutch disc loosely received within the recessed portion of the bearing member and formed with a hub member through which the hand crank extends and which has cam notches in the end thereof, a retaining plate 50 fitted to the bearing member to hold the clutch disc in position and formed with an opening through which the hub member projects, clutch members cooperating with the clutch disc to permit rotation thereof in one 55 direction and prevent rotation thereof in the opposite direction, the clutch disc being comparatively large and the clutch members acting at the periphery thereof so that an effective clutch action is obtained, and arms 60 projecting laterally from the hand crank and arranged to enter the cam notches of the hub when the hand crank is moved longitudinally to bring it into engagement with the engine shaft, said arms cooperating with the 65 notches to rotate the hub and clutch disc with the hand crank when the latter is turned in one direction and to move the hand crank longitudinally to disengage it from the engine shaft when the hand crank is rotated in 70 the opposite direction. 75

In testimony whereof I affix my signature.
OSCAR CROCKETT.
